[57] CLAIM

The ornamental design for a lift truck converter, as shown and described.

DESCRIPTION

FIG. 1 is a front elevational view of a lift truck converter showing our new design;

FIG. 2 is a rear elevational view thereof;

FIG. 3 is a top sectional view taken along line 3—3 of FIG. 1.

FIG. 4 is a left side elevational view thereof;

FIG. 5 is a top plan view thereof;

FIG. 6 is a bottom plan view thereof;

FIG. 7 is a right side elevational view thereof; and

FIG. 8 is a reduced perspective view thereof.

FIG. 5

FIG. 6

FIG. 7

FIG. 8
